UNITED STATES PATENT OFFICE.

MARVIN D. FINK, OF NEW YORK, N. Y.

CLOSURE FOR CONTAINERS.

1,371,778.

Specification of Letters Patent. Patented Mar. 15, 1921.

Application filed February 10, 1920. Serial No. 357,547.

To all whom it may concern:

Be it known that I, MARVIN D. FINK, a citizen of the United States, and resident of the city of New York, borough of Manhattan, in the county and State of New York, have invented a new and Improved Closure for Containers, of which the following is a full, clear, and exact description.

This invention relates to improvements 10 in the construction of the delivery ends of containers and has particular reference to a closure in the delivery opening of the same.

It has been observed that in the construction of containers such as collapsible tubes for the reception of tooth paste, pharmaceutical preparations, cosmetics and the like which are now in general use and on the market, an exteriorly threaded delivery 20 neck is provided and the delivery opening therethrough is closed by means of a removable threaded cap. Use of such a cap is objectionable for the reason that the same is often misplaced or dropped and lost in 25 the waste pipe of a wash basin.

It is therefore one of the principal objects of the present invention to improve the construction of the delivery end of a container of this character by providing a closure which forms a permanent part of the delivery end of the container.

Another object of the invention is to provide a closure for the delivery opening which is provided with means adapted to 35 coact with the container neck to position and retain the closure in sealed contact with the neck when the closure is disposed over the delivery opening.

A further object of the invention is to 40 provide a closure which may be manufactured as a separate element, the same being so constructed as to permit of a ready assembly of the same with the neck.

A still further object of the invention is 45 to provide a device of the character described which is simple in construction, efficient in purpose and inexpensive to manufacture.

With these and other objects in view 50 which will be more apparent as the nature, purpose and operation of the device is better understood from the following description and claims, reference is made to the ac-

companying drawings forming a part of this application and in which— 55

Figure 1 is a perspective view of the container with the improved construction of the delivery end clearly illustrated as associated therewith.

Fig. 2 is a fragmentary enlarged detail 60 view of the delivery end.

Fig. 3 is an end view of the same.

Fig. 4 is a vertical sectional view therethrough taken on the line 4—4 of Fig. 2.

Referring to the drawings by characters of reference which denote like parts throughout the several views thereof 10 designates the container body and 11 the delivery end which is provided with a substantially rectangular oblong neck 12 having a 70 delivery opening 13 therethrough disposed at one side of the horizontal center thereof. The upper surface of the neck 12 is provided with a horizontal flat portion 14 disposed toward the same side of the neck through 75 which the delivery opening extends. Trunnions 15 project outwardly from the long sides of the neck 12, substantially in alignment with the delivery opening 13 and an arcuate portion 15^a is provided on the upper 80 surface of the neck concentric with the axis of the trunnions 15. One extremity of said arcuate portion merges into the flat portion 14 and the opposite extremity intersects the vertical end wall 16. The closure 85 member comprises a head 17 having spaced depending parallel legs 18 formed integral therewith, the lower extremity of said legs being formed to provide hooked terminals 19 which receive the trunnions 15 in order 90 to swingingly associate the closure member with the neck 12. The underside of the head is recessed as at 20 for the reception of a resilient gasket 21 which is designed to 95 contact with the upper surface of the neck to normally exert pressure between the head and the upper surface. A bendable pin 22 is formed on the end wall 16 adjacent one of the side walls, the length of said pin being such as to dispose its free extremity 100 within the radial path of movement of the outer surface of the gasket when the closure member is swung upon its pivot. This permits of the easy application of the closure to the neck in assembling the same. After 105 the closure member has been applied and

the closure member has been applied and

swung upon its pivot to position the outer surface of the gasket in contact with the upper surface of the neck, the pin 22 is bent around the corner of the neck to dispose 5 said pin along the side of the same in order to prevent the removal of the closure member from the neck.

In order to provide means to retain the gasket in sealing contact with the neck over 10 the delivery opening, the legs 18 are cut away as at 23 and said cut away portions are each provided with a depression 24. Bosses 25 are formed on the side faces of the neck and the same are provided with lugs 26, 15 which are adapted to receive the depressions 24 for co-acting engagement therewith to prevent casual swinging movement of the closure member. The interengagement of the depression 24 with the lugs 26 is effected 20 by the inherent quality of the resilient gasket which tends to maintain the co-acting engagement and relation of the depressions with said lugs. The formation of the hooked terminals 19 of the legs serves to permit of 25 sliding movement of the closure on the trunnions. The arcuate surface 15 is provided with an enlargement 27 which is designed to co-act with the gasket to retain the closure member in an open position.

30 The operation is as follows: to open the closure member for gaining access to the interior of the container, it is only necessary to exert a slight downward pressure on the head 17, at the same time forcing the same 35 toward the enlargement 27, the downward movement of the closure member serving to disengage the depressions 24 from the lugs 26. As the gasket comes in contact with the enlargement 27, a frictional binding between 40 the two will be effected and serve to retain the closure member in an open position. Should the closure member be advanced far enough to pass the enlargement 27, one of the legs 18 will contact with the pin 22, 45 thereby preventing the separation or possible loss of the closure member. When the closure member is swung to a position to close and seal the delivery opening, the head is forced slightly downward against 50 the inherent resiliency of the gasket until the depressions 24 engage over the lugs 26, the expansion of the gasket serving to lock the depressions over the lugs. If for any reason it should be found necessary to 55 move the closure member entirely from the neck 12, it is only necessary to bend the pin 22 to project it at right angles with respect to the wall 16. The closure member is then free to be swung to a horizontal position from which position the hook terminals 19 may be readily disengaged from the 60 trunnions 15.

While there has been illustrated and described a single and preferred form of the 65 invention, it is understood that the same is

merely illustrative of one embodiment of the same and variations and changes in the details of construction which fall within the scope of the claims, may be resorted to when found expedient.

Having thus described my invention, what I claim as new, and desire to secure by Letters Patent, is—

1. In a container neck having a delivery opening therethrough, a closure therefor 70 having a detachable sliding pivotal connection therewith, means formed respectively on the closure and the neck adapted to co-act with each other to position and retain the closure in sealed contact with the neck over the delivery opening and a bendable pin carried by the neck adapted to be respectively bent to positions for limiting or permitting the free swinging movement of the closure in one direction.

2. In a container neck having a delivery opening therethrough, a closure therefor 75 having detachable sliding pivotal connection therewith, bendable means adapted to be bent to positions for preventing entire detachment of said closure from the container, means formed respectively on the closure and the neck adapted to co-act with each other to position and retain the closure in sealed contact with the neck over the delivery opening, and means on the neck adapted to co-act with the closure for retaining the same in an open position.

3. In a closure for containers the combination with a neck formed thereon and having a delivery opening therethrough, of a cover member comprising a head, a resilient gasket carried thereby and adapted to contact with the outer end of said head, spaced parallel legs on said head adapted to straddle the neck, means for detachably pivoting the arms to said neck, means provided on the legs, means provided on the neck adapted to co-act with the means on the legs to position and retain the gasket in sealed contact with the outer end of the neck over the delivery opening, and means formed on the neck adapted to co-act with the gasket to retain the cover member in open position.

4. In a closure for containers the combination with a neck formed thereon and having a delivery opening therethrough, of a cover member comprising a head, a resilient gasket carried thereby and adapted to contact with the outer end of said head, 100 spaced parallel legs on said head adapted to straddle the neck, means for detachably pivoting the legs to said neck, means provided on the legs, means provided on the neck adapted to co-act with the means on the legs to position and retain the gasket in sealed contact with the outer end of the neck over the delivery opening, means formed on the neck adapted to co-act with the gasket to retain the cover member in open posi- 105

tion, and means formed on the neck adapted to co-act with the legs to prevent the removal of the cover member from the neck.

5. A container and closure therefor, comprising a rectangular neck having one side portion of its top flattened and the remainder of arcuate formation merging respectively into said flattened portion and intersecting one of the end walls of said 10 neck, the said neck having a delivery opening therethrough communicating with the flattened portion, trunnions projecting from opposite sides of said neck concentric to the arcuate top portion, a cover member having 15 a head and spaced parallel legs provided with hooks adapted to engage the trunnions for obtaining sliding pivotal association of the cover with the neck, a bendable pin projecting from the end wall intersected by 20 the arcuate top portion, said lug when bent around the corner of the neck serving to limit free swinging movement of the cover and when straightened permitting the removal of the cover from the neck.
25. 6. A container having a neck oblong in cross section, trunnions projecting from the opposite side walls thereof, the top of said neck having a flat portion and an arcuate portion merging into said flat portion and 30 intersecting one end wall, said neck having a delivery opening therethrough communicating with the flat portion, a cover having a head and parallel legs depending therefrom, the free extremities of said legs hav-

ing detachable sliding pivotal association 35 with the trunnions, a resilient gasket carried by the head and adapted to frictionally engage the top of said neck, and a bendable pin projecting from the end wall of the neck intersected by the arcuate portion of the 40 top, said lug when bent around the corner of the neck serving to contact with one of the legs whereby to limit the free swinging movement of the cover to permit of its detachment from the neck.

45. 7. The combination with a container having a neck provided with a delivery opening and trunnions projecting from the opposite sides thereof, of a closure for said opening comprising a head, a resilient 50 gasket carried thereby and adapted to contact with the upper surface of the neck, spaced parallel legs formed on said head and adapted to straddle the neck, the free terminals of said legs having hooked portions adapted to engage the trunnions to obtain a sliding pivotal mounting for the closure on the neck, and means for retaining the closure in a position for sealing the delivery opening, said means comprising 55 bosses formed on the opposite sides of the neck, lugs depending therefrom, cut away portions in the legs, and depressions in the cut away portions, the gasket serving to effect engagement of said depressions with 60 the lugs.
